CAR

Abram E. Smith and William H. Runkel, Chicago, Ill., assignors to Union Tank Car Company, Chicago, Ill., a corporation of New Jersey

Application April 10, 1933, Serial No. 665,353

13 Claims. (Cl. 105 -247)

This invention relates to a novel and improved form of car, more particularly one for handling finely divided products, such as fuller's earth. Fuller's earth, in particular, presents certain difficulties in handling in large quantities. It has been customary in the past to handle it in small sacks because of the difficulty of handling in bulk. Such difficulties are overcome by our invention, as will be better understood from the following 10 description and the annexed drawings, in which we have shown a car embodying a selected form of the invention and in which:

Fig. 1 is a vertical view, partly in elevation and partly in section, showing one form of car with 15 the invention applied thereto;

Fig. 2 is a horizontal view, partly in section and partly in plan, of the structure appearing in Fig. 1;

Fig. 3 is a section on the line 3—3 of Fig. 1;

20 Fig. 4 is a cross-section on an enlarged scale showing one form of knife which may be employed;

Fig. 5 is a detail perspective view of a form of vibrator which may be used in the practice of 25 the invention;

Figs. 6, 7, and 8 are fragmentary views showing part of the bottom sheet of a car and illustrating successive steps in the formation of a 30 hopper therein;

Fig. 9 is an elevation taken at right angles to Fig. 8.

The car shown herein is a tank car having a generally cylindrical shaped body 1 and provided with the usual frame and supporting wheels, the 35 details of which will not be discussed. According to our invention, this car is divided into a plurality of compartments, here shown as three in number, the compartments being formed by transversely extending partitions 2 extending vertically from the bottom to the top of the car. The end compartments have their end walls formed of slope sheets 3.

At the bottom of each compartment is disposed a hopper 4 having downwardly inclined walls arranged approximately at the same angle to the horizontal as the slope sheets 3. Preferably, the bottom of the car is formed of a single sheet 5 having holes therein surrounded by downwardly extending walls 6 forming the upper parts of the 45 respective hoppers. These downwardly extending walls are preferably integral with the bottom, and are of the same thickness as the bottom sheet, this sheet being preferably formed with a cylindrical surface corresponding to the cylindrical 50 cal form of the body of the car. The openings

in the bottom sheet may be curved as shown in Figs. 1, 2, and 3, or may have straight sides as shown in Figs. 6, 7, 8, and 9. In Figs. 1, 2, and 3, they are shown as curved in form, either round or elliptical, and the upper edges 7 of the walls 6 in the end compartments are approximately tangent to the lower edge 8 of the slope sheets in those compartments. In the center compartment and at the ends of the end compartments opposite the slope sheets, aprons 9 are provided, likewise approximately tangent to the upper edge 7 of the wall 6 and inclined upwardly at approximately the same slope as the wall 6. Since the bottom sheet and the side walls of the car body are all arcuate in form, being part of the cylindrically shaped body of the car, it will be seen that only upwardly extending surfaces are provided, both in the hopper and above it.

For a purpose which will appear later, the lower part 10 of the hopper is preferably formed of 20 relatively thin sheet metal riveted to the downwardly extending walls, as at 11, or otherwise secured thereto and forming substantial continuations of these walls. A suitable closure 12 is provided for the bottom of each hopper extending over the outlet 13. The details of this closure may be varied considerably, and since they are not essential to an understanding of this invention, they will not be further discussed.

Extending through the wall of each hopper, and 25 spaced around the periphery thereof, are air jets or nozzles 14, a plurality of such jets being shown herein and so arranged as to discharge air or other suitable fluid horizontally. One of the advantages of having the hopper of a curved form 30 as appearing in a horizontal view thereof is that the air jets may be conveniently arranged to give a better swirling action to the material in the hopper. The jets may be of any form desired, so as to give the desired cross-section to the stream 35 issuing therefrom. They may be placed on the same horizontal plane or on different planes, as shown in Fig. 3, but preferably they all point in the same rotative direction. For example, if the material is to be given a swirling motion in a 40 clockwise direction, all jets discharge in that direction.

Also mounted on the bottom part 10 of each 45 hopper is a pair of wedge-shaped holders 15 within which fits a correspondingly shaped pad on a bracket 16 supporting a vibrator 17 of conventional or other suitable form. Vibrators of this general type are well known in the art, and no detailed description thereof will be given. Obviously also, the brackets may, if preferred, be 50

fastened in place by suitable bolts. Similar holders 15 may be placed on the under side of the slope sheets 3, as indicated in Fig. 1.

Extending across the top of each hopper is a shaft 18 preferably disposed in bushings 19 on opposite sides of the car and having one or both ends 20 thereof shaped to receive a wrench handle and disposed outside of the car. Within the car, the shaft carries an agitator, here shown as 10 comprising a sleeve 21 fastened on the shaft and having a plurality of knife blades 22 and 23 extending upwardly into the body of the car or downwardly into the hopper. These blades may be connected by cross bars 24 which act as braces 15 to hold the blades together and also for another purpose which will be explained directly.

Air may be applied to the jets 14 from suitable piping 25 which may be connected to any convenient source of compressed air and which may 20 also furnish air for operation of the vibrator 17, this air being supplied to a suitable inlet 26 on the vibrator. Preferably, each compartment is provided with one or more openings in the top of the car indicated at 27 and provided with suitable removable closures.

The operation of the invention will now be briefly described. Fuller's earth, in particular, is a material which, when handled in bulk, packs very closely and has great cohesion. For example, it has been found that an ordinary use of 30 an air jet in a fixed path will result merely in cutting a channel through the material without substantially disturbing it, as the material has an angle of repose of approximately 90°. In other words, the face of the material will remain vertical, and unusual devices must be employed for breaking it up and removing it.

The car illustrated and described herein has been found to successfully solve the problem. It 40 will be seen that the material will contact only with upwardly extending metallic surfaces, to which it will adhere to a minimum extent. Therefore, when the material in the middle of a compartment or at any point remote from the 45 walls thereof begins to move downwardly, the power of cohesion within the mass will normally be greater than the power of adhesion to the metallic surfaces. We also contemplate surfaces formed of other material than metal, to which the power of adhesion of the material is relatively small.

Now assuming that a car of fuller's earth is to be unloaded, the closure 12 over the discharge outlet of one hopper and its corresponding compartment is removed and suitable conveying apparatus may be attached thereto in a manner well known in the art. Next, a vibrator is fastened in place on one wall of the hopper and put in operation. This appears to loosen the material 50 immediately adjacent the discharge outlet and to some extent throughout the hopper. Then the agitator is operated by means of a wrench applied to the end 20 of the shaft 18 or by other suitable means. The blades 22 of the agitator preferably 55 have knife edges 22', as shown in Fig. 4, and may be wedge-shaped, as indicated, or of any other suitable form, to help in agitating the material, both in the hopper and in the body of the car. The cross bars 24 also aid in breaking down the 60 material, and, in fact, these bars, with the blades, form a sort of grill, as plainly shown in Fig. 3. Next, air is supplied to the line leading to the jets 14, which will cause the material to form a vortex because of the swirling action set up by 65 the air. The material, having been first loosened

somewhat by the vibrator, will respond to the action of the air and will probably become more or less aerated. Vibrators may also be used on the slope sheets 3, these sheets in the form shown bounding the space at the end of the car, and a 5 wall of this space being provided with a manhole 28 to give access to this space.

We have described above the various steps which are taken and in the order which at present seems to give the best results, although it is 10 to be understood that this order may be varied as desired and as found most expedient. If found necessary, an air line may be put through one of the openings 27 in the upper part of a compartment, and any residue of material may be blown 15 out through the hopper by this means.

Referring now to Figs. 6, 7, 8, and 9, we have shown therein a part of a hopper of different form than that appearing in Figs. 1, 2, and 3, and have illustrated one way in which such a 20 hopper may be formed.

In Fig. 6, we have shown a portion of the bottom sheet 5 disposed between two adjacent partitions before the hopper is formed therein. While the partitions have been shown in Figs. 6, 25 7, and 8, it will of course be understood that the hopper may be formed either before or after the partitions are put in place, and even before the sheet is put in the car, if found desirable.

The sheet is first cut to form slits therein, here 30 shown as a slit 29 extending transversely of the length of the sheet and meeting at its opposite ends slits 30 extending generally transverse of the sheet but preferably curved, as indicated, so that their central portions are nearer each other than 35 their ends. This construction results in the formation of two leaves 31 on opposite sides of the slit 29 and also of leaves 32 within the arcs of the curved slits 30.

The next step is to bend the leaves 31 and 32 40 downwardly, as indicated in Fig. 7, this bending down forming, in this instance, straight top edges 33 and 34 for the hopper. The leaves 31 are bent again at 36, preferably along a curved surface so as to form a rounded corner, so that the 45 corners 35 thereof form part of the walls of the hopper extending transversely of the leaves 31.

The process thus far described results in a retention of the thickness of the sheet, as no substantial stretching or drawing thereof has taken 50 place. The next step is to add to the structure thus partly formed, by placing inserts 37 in place, these inserts being plates of such shape that they will fit into the spaces between the bent-down leaves 31 and 32, and of the same thickness as 55 those leaves. A detailed description of this shape is not deemed necessary. These inserts may now be welded along the edges which contact with the bent-down leaves 31 and 32, as indicated at 38, for example. After welding, any excess metal on 60 the interior of the hopper may be smoothed off so as to prevent formation of rough surfaces and so as to provide a smooth hopper surface.

After the inserts have been fastened in place, the hopper may be completed by the addition of 65 bottoms 10 of thin sheet metal, as described above, or, under some circumstances, the hopper formed by the process described above may be considered complete. Air jets are likewise installed, as in the form shown in Figs. 1, 2, and 3, 70 but for the sake of simplicity these jets, together with the additional plates, have been omitted from Figs. 6, 7, 8, and 9.

The method described above can be used with various shapes of hoppers, as, for example, the 75

shape shown in Figs. 1, 2, and 3. While, for the sake of convenience, one continuous bottom sheet is shown in Figs. 1, 2, and 3, nevertheless it is obvious to those skilled in the art that the same 5 method can be practiced with smaller sheets, for example with sheets of such a size as to form individual hoppers which may then be riveted in place on a bottom sheet already on the car.

While we have shown the invention as embodied in a specific form, it is to be understood that various changes in details may be made without departing from the scope of the invention, and we therefore do not intend to limit ourselves except by the appended claims.

15 We claim:

1. A car having a bottom comprising a sheet of relatively thick metal, said sheet having an opening therein surrounded by downwardly extending walls integral with said sheet, a hopper 20 having side walls formed in part by said downwardly extending walls of the opening and in part by downward continuations thereof formed of relatively thin sheet metal secured to the relatively thick metal of the bottom sheet, and a 25 closure for said hopper removable to permit withdrawal of the contents of the car and hopper.

2. A car having a bottom comprising a sheet of relatively thick metal, said sheet having an 30 opening therein surrounded by downwardly extending walls integral with said sheet, a hopper having side walls formed in part by said downwardly extending walls of the opening and in part by downward continuations thereof formed 35 of relatively thin sheet metal secured to the relatively thick metal of the bottom sheet, a closure for said hopper removable to permit withdrawal of the contents of the car and hopper, and means for detachably securing a vibrator to said hopper 40 in position to operate on the thin-walled portion thereof.

3. A car having a bottom comprising a sheet of relatively thick metal, said sheet having an opening therein surrounded by downwardly extending walls integral with said sheet, and a 45 hopper having side walls formed at least in part by said downwardly extending walls of the opening, said walls forming a substantially continuous horizontally curved interior surface free 50 of corners.

50 4. A car having a bottom comprising a sheet of relatively thick metal, said sheet having an opening therein surrounded by downwardly extending walls integral with said sheet, a hopper having side walls formed at least in part by said 55 downwardly extending walls of the opening, said walls forming a substantially continuous horizontally curved interior surface free of corners, and a downwardly extending continuation 60 formed of relatively thin sheet metal and likewise forming a substantially continuous curved interior surface free of corners.

5. A car having an arcuate shaped bottom sheet cut along a central line extending lengthwise thereof and along lines at the end of said central cut and transversely thereof, said transverse cuts having their central portions nearer each other than their ends and the longitudinal and transverse portions defined by said cuts bent 70 downwardly to form hopper walls.

6. A car having an arcuate shaped bottom sheet cut along a central line extending lengthwise thereof and along lines at the end of said central cut and transversely thereof, said transverse cuts having their central portions nearer 75

each other than their ends and the longitudinal and transverse portions defined by said cuts bent downwardly to form hopper walls of the same thickness as that of the sheet, and inserts disposed between the bent-down portions of the sheet and secured thereto to form part of the hopper. 5

7. A tank car having a cylindrically-shaped body with the axis of the cylinder extending horizontally, thereby providing a bottom sheet of 10 arcuate form, said bottom sheet having an opening therein with a continuous curved edge, a hopper having a downwardly extending wall likewise continuously curved horizontally and having a top edge of the same curvature as the edge 15 of said opening, said top edge of the hopper wall and said edge of the opening being integrally united.

8. A tank car having a cylindrically shaped body with the axis of the cylinder extending horizontally, thereby providing a bottom sheet of 20 arcuate form, said bottom sheet having an opening therein with a continuous curved edge, a hopper having a downwardly extending wall likewise continuously curved horizontally and having 25 a top edge of the same curvature as the edge of said opening, said top edge of the hopper wall and said edge of the opening being integrally united, and an inclined apron extending upwardly from said hopper and disposed transversely of the car and forming a partial continuation of said hopper wall. 30

9. A tank car having a cylindrically-shaped body with the axis of the cylinder extending horizontally, thereby providing a bottom sheet of 35 arcuate form, said bottom sheet having therein an opening with an edge which is continuously curved horizontally, a hopper having an outlet at its bottom and having a downwardly extending wall which is likewise continuously curved 40 horizontally and whose top edge has the same curvature as the edge of said opening, said top edge of the hopper wall and said edge of the opening being integrally united, an agitator comprising a shaft extending horizontally across said 45 hopper substantially diametrically thereof and journaled in the longitudinal sides of the car adjacent the top of the hopper, blades on said shaft extending downwardly a substantial distance into said hopper and upwardly a substantial distance into said body, said shaft having an end disposed outside the car and of non-cylindrical shape to receive a detachable handle to rock the shaft. 50

10. A tank car having a cylindrically-shaped body with the axis of the cylinder extending horizontally, thereby providing a bottom sheet of 55 arcuate form, said bottom sheet having therein an opening with an edge which is continuously curved horizontally, a hopper having an outlet at its bottom and having a downwardly extending wall which is likewise continuously curved horizontally and whose top edge has the same curvature as the edge of said opening, said top edge of the hopper wall and said edge of the opening 60 being integrally united, an inclined apron extending upwardly from said hopper and disposed transversely of the car and forming a partial continuation of the hopper wall, an agitator comprising a shaft extending horizontally across said 65 hopper substantially diametrically thereof and journaled in the longitudinal sides of the car adjacent the top of the hopper, blades on said shaft extending downwardly a substantial distance into said hopper and upwardly a substantial 70 distance into said body. 75

tial distance into said body, said shaft having an end disposed outside the car and of non-cylindrical shape to receive a detachable handle to rock the shaft.

- 5 11. A tank car having a cylindrically-shaped body with the axis of the cylinder extending horizontally, thereby providing a bottom sheet of arcuate form, said bottom sheet having therein an opening with an edge which is continuously curved horizontally, a hopper having an outlet at its bottom and having a downwardly extending wall which is likewise continuously curved horizontally and whose top edge has the same curvature as the edge of said opening, said 10 top edge of the hopper wall and said edge of the opening being integrally united, an agitator comprising a shaft extending horizontally across said hopper substantially diametrically thereof and journaled in the longitudinal sides of the car adjacent the top of the hopper, blades on said 15 shaft extending downwardly a substantial distance into said hopper and upwardly a substantial distance into said body, said shaft extending

outside the car, and means outside the car for operating said shaft.

12. A car having an arcuate shaped bottom sheet with an opening therein, the material of said sheet being bent downwardly substantially throughout the periphery of the opening to form the upper portions of hopper walls, and plates welded to said upper portions and extending downwardly therefrom to complete the hopper walls. 5

13. A car having an arcuate shaped bottom sheet with an opening therein formed by a longitudinally extending central cut and transversely extending cuts at the opposite ends thereof, said transversely extending cuts being convex towards each other, thus providing four leaves, which leaves are bent downwardly to form the upper portions of hopper walls, and plates welded to said upper portions and extending downwardly therefrom to complete the hopper walls. 10 15 20
